CLAIM

The ornamental design for a display screen portion with graphical user interface, as shown and described.

DESCRIPTION

FIG. 1 is a front view of a display screen portion with graphical user interface showing our new design;

FIG. 2 is a second embodiment thereof;

FIG. 3 is a third embodiment thereof; and,

FIG. 4 is a fourth embodiment thereof.

The broken lines showing a portion of the display screen and the broken lines within the graphical user interface depict environmental subject matter only and form no part of the claimed design.

1 Claim, 4 Drawing Sheets(56)
